UNITED STATES PATENT OFFICE.

JOHN ERICKSON, OF CHICAGO, ILLINOIS, ASSIGNOR TO AUTOMATIC ELECTRIC COMPANY, OF CHICAGO, ILLINOIS, A CORPORATION OF ILLINOIS.

MEASURED-SERVICE TELEPHONE SYSTEM.

1,312,965.

Specification of Letters Patent. Patented Aug. 12, 1919.

Application filed December 8, 1917. Serial No. 206,317.

To all whom it may concern:

Be it known that I, JOHN ERICKSON, a citizen of the United States of America, and a resident of Chicago, Cook county, and 5 State of Illinois, have invented certain new and useful Improvements in Measured-Service Telephone Systems, of which the following is a specification.

My invention relates in general to measured service systems and particularly to meter control circuits for use in automatic telephone systems. More specifically the invention provides an improved metering arrangement which is especially adapted to be 15 placed at the subscriber's substation either on a single or party line station and which involves a number of novel and highly useful features which will be pointed out and described hereinafter.

20 In my prior application Serial #181,727, filed July 20, 1917, I have shown a meter of this character. The present application is in the nature of an improvement upon said prior application and while the prior application shows varied forms of such a meter which accomplishes some of the required results yet my present application accomplishes all of the results which were taken care of by the former case in an improved 25 manner and also accomplishes further highly necessary results which were not taken care of in my prior application.

30 Among the objects of my invention is to provide an improved substation meter which is absolutely fool proof, that is, one which it is impossible for a subscriber to prevent the operation of and which will operate once and only once for each successful call and which it is impossible to operate to register 35

40 an unsuccessful call.

Further objects are to arrange the circuits of such a meter so that when the receiver is removed to make a call, the talking circuit is clear of all windings which are associated with the meter, and also after the 45 call is completed, and the meter is operated, the talking circuit is again cleared of all such windings. Means is also provided to prevent a subscriber from removing the meter from connection with the telephone until 50 it is registered. The above features it will

be seen are especially valuable in connection with polystation lines, in which it is desired to allow a subscriber to listen in on his line before making a call without giving his meter a chance to operate because of the existence of an answered call from some other station on his line.

Referring to the drawings, in the figure I have shown diagrammatically a preferred 60 form of a substation circuit embodying my invention together with a fragmentary showing of certain exchange circuits, which may be used to connect with a called subscriber, in order to show the method of controlling 65 said meter.

The complete substation is shown at the left of said figure and is indicated by the reference character A; at C are shown the wipers of a line or selector switch at the exchange individual to the line of substation A which is used to select an idle automatic connector switch E only the line and back bridge relay of which are shown. The connector E is shown with its wipers in connection with a second or called substation D. 70

Referring to the figure the substation A comprises a receiver 1, transmitter 2, receiver hook 3, ringer 4, and condenser 5. Being an automatic substation there is also 80 provided the calling device or impulse sender CD provided with the usual impulse springs 6 and 7 and a shunt spring 8. This calling device is of the type in which the impulse springs are controlled by a finger hole dial 85 to produce series of interruptions in the line circuit in accordance with the digit of a called number. Such a calling device is shown in the British patent to Dicker #29,654 of 1910. 90

In addition to the parts above enumerated there is provided a meter M comprising an operating magnet 9, and a polarized controlling relay 10, the armature of which normally maintains the armature of the operating magnet in energized position by means of a pair of escapement springs 11 and 12. The meter M may be of any well known type comprising a series of number wheels which are adapted to be operated one step at each 95 completed call to register the total number 100 of such calls.

The line conductors 20 and 21 extend to the exchange, where they terminate in the wipers of an individual switch C. The line switch C may be of any approved type 5 adapted to operate upon the closure of the line circuit at the substation A to extend the line conductors 20 and 21 into connection with a trunk line 22 and 23 which terminates in a connector switch E which in turn 10 has direct access to a group of subscribers' lines one of which is the line of substation D. The connector E may also be of any approved two-wire type, which has the provision of means whereby, upon the response 15 of a called subscriber, the incoming line conductors are reversed with regard to their connection to the line or controlling relay. Thus the line conductors 22 and 23 before terminating in the windings of the line relay 24, pass through the reversing springs on the back-bridge relay 25. Switches similar to those shown are of similar construction to those shown in U. S. Letters Patent 20 to Frank Newforth Reissue #13,901.

Having given a brief description of the apparatus I will now proceed to explain the mode of operation in detail. The substation A may be one of the stations on a party line, in which case one or more other substations 30 similar in all respects to the substation A may be connected in bridge of the line conductors 20 and 21.

Assuming the substation A to be one of the stations upon a party line the subscriber 35 will first remove the receiver 1 from the switch hook 3 to listen in. A circuit is thereby closed from the line conductor 20, through the switch hook 3, spring 13, receiver 1, transmitter 2, impulse springs 7 and 6, 40 springs 14 and 15, springs 16 and 17, and to the line conductor 21. It will be seen that the windings 18 and 19 of the polarized coil 10 are at this time excluded from the line circuit and that the subscriber may listen in 45 to ascertain whether the line is busy or idle without operating said meter control relay. Assuming the line to be idle, the calling party will then rotate his finger hole dial (not shown) to separate the springs 6 and 7 50 a number of times to send a number of impulses over his line circuit according to the number of the desired party's line. It may be noted here that as soon as the receiver was removed a circuit was closed for the 55 usual line or controlling relay of the line switch C which thereupon operated to select an idle trunk 22 and 23 and to connect the line conductors 20 and 21 therewith by means of the wipers 26 and 27. As soon as the 60 calling device is first rotated a pin on said dial leaves the spring 8 and allows said spring to make contact with the spring 7. This closes a circuit for the winding 19 of the polarized relay 10 in multiple with the

transmitter and receiver and in series with the line 20—21 extending from the spring 13, through the winding 19, springs 8 and 7, springs 14 and 15, and 16 and 17 to the conductor 21. Battery at this time will flow from the battery B through the upper winding of line relay 24, springs 28 and 29, conductor 22, wiper 26, conductor 20, switch-hook 3, spring 13, through the receiver and transmitter in multiple with the winding 19, to springs 8 and 7, spring 6, springs 14 75 and 15, springs 16 and 17, conductor 21, wiper 27, conductor 23, springs 30 and 31, and lower winding of relay 24 to ground.

The current in this circuit is of such a direction that the armature 32 of the relay 80 10 is attracted toward the upper core, thereby pressing the spring 12 in a downward direction and removing a tooth from engagement with an upward extending arm 33 on the armature of the meter magnet 9. The 85 armature 33 thereupon falls back part way until the bushing on the arm 33 meets another escapement tooth on the underside of the spring 11. This movement of the arm 33 causes the said armature to fall back 90 only a portion of its movement, thereby causing the arm 34 which is attached to the armature 33 to be moved to the right to operate by means of bushings which are located at intervals on the arm 34, certain 95 spring contacts as follows: The spring 15 is moved out of engagement with the spring 14 but not into engagement with the spring 35. The spring 36 is moved into engagement with the spring 37, while the springs 100 16 and 17 are moved into engagement with the spring 38. The results of this operation of the arm 34 are as follows: The winding 19 of the polarized relay 10 is short circuited by the closure of the springs 105 36 and 37 which also short circuits the transmitter and receiver so as to prevent the impulses caused by the separation of the springs 6 and 7 from causing any annoyance to the subscriber through the receiver 1. 110 The movement of the spring 15 removes the short circuit which normally existed around the winding 18 of the polarized relay 10. The movement of the springs 16 and 17 prepares a circuit for the meter magnet 9 extending from the back contact 39 of the switch hook through the said meter magnet 9, springs 38 and 17, to the line conductor 21. The separation of the springs 6 and 7 115 in response to the operation of the calling device for the digits of the called number operates to open and close a circuit for the line relay 24 of the connector E, which circuit may be traced as follows: From ground to the lower winding of the line relay 24, 120 springs 31 and 30, of the back bridge relay 25, line conductor 21, springs 17 and 16, winding 18 of the polarized relay 10, springs 125 31 and 30, of the back bridge relay 25, line conductor 21, springs 17 and 16, winding 18 of the polarized relay 10, springs

6 and 7 of the calling device CD, shunt spring 8, springs 37 and 36, contact 13, switch hook 3, line conductor 20, springs 29 and 28 of the back bridge relay 25 and 5 through the upper winding of the line relay 24 to battery B.

The current flow in this circuit is in such a direction that the polarized relay 10 will be operated to attract its armature toward 10 the upper pole piece, which operation has no effect at this time as the arm 33 has moved out of engagement with the escapement tooth on the spring 12. Line relay 24 in response to the impulses for these digits 15 operates the connector E to connect by means of its wipers 40 and 41 with the line leading to the substation D. When the calling device CD restores to normal after delivering the necessary impulses the spring 8 20 is again disconnected from the spring 7, thereby removing the short circuit or shunt circuit from the transmitter 2 and receiver 1 and leaving the transmitter and receiver connected in series with the winding 18 of 25 the polarized relay 10 and the line relay 24 of the connector E. The connector E operates automatically at this time in a manner well known to signal the called subscriber through the medium of his ringer 42. The 30 subscriber D upon hearing his signal removes his receiver from the hook, thereby closing a circuit for the back bridge relay 25 of the connector E which extends from ground through the lower winding of said 35 relay 25, wiper 41, to and through the receiver and transmitter of the substation D, wiper 40, and the upper winding of the relay 25 to battery. The relay 25 upon energizing over the above circuit operates to reverse 40 the connections of the line relay 24 to the trunk conductors 22 and 23 which causes a reversal of the current through said trunk conductors and the line of the substation A in series. This reversal of current through 45 the winding 18 of the polarized relay 10 causes the armature 32 to be attracted to the lower pole piece of said relay, thereby raising the spring 11 to remove an escapement tooth on said spring out of engagement with the arm 33. The arm 33 thereupon moves to the right due to spring tension and causes the arm 34 to be moved farther toward the right. This movement of the arm 34 causes the tooth 43 on the end of said arm to fall 50 into one of the teeth on the wheel 44 and also causes the spring 15 to make contact with the spring 35, thereby restoring the short circuit about the winding 18 of the polarized relay 10 and putting the armature 55 of the meter magnet in such a position that when the meter magnet is energized the wheel 44 will be operated to step the usual counting wheels one step to register the call. The subscribers at substations A and D may

now converse over the conductors which are 65 shown with heavy lines. It will be seen that this talking circuit is clear of all windings which are associated with the meter mechanism and that no matter what changes in current flow may take place in said talking 70 circuit there is no chance for the meter controlling relay to be again operated. After the conversation is completed the connection is released by the hanging up of the receiver at the calling station in the usual 75 manner. The closure of contact by the switch hook 3 with the spring 39 closes a circuit for the meter magnet 9 which may be traced as follows: From battery through the usual line relay of the line switch C to 80 the line conductor 20, switch hook 3, contact 39, meter magnet 9, springs 38 and 17, line conductor 21 and to ground at the line switch C.

The meter magnet 9 is of comparatively 85 high resistance and does not allow the line relay of the line switch C to be energized at this time. The magnet 9, however, energizes and operates the meter through the medium of the tooth 43 and the wheel 44, restores the springs 14, 15, 36, etc. to their normal position and restores the upward extending arm 33 to its normal position behind the escapement tooth on the spring 12. The restoration of the springs 14, 15, etc. to 90 their normal position again places the substation circuits in their normal position and leaves the circuits ready for another call from the substation A. Let us assume now that the subscriber A lifted his receiver to 100 initiate a call and operate his calling device CD for the first digit of the called number. In this case as before pointed out the winding 19 of the polarized relay 10 is first thrown across the talking circuit and operates to allow the armature of the meter magnet 9 to take its first step, which step removes the winding 19 from the talking circuit and replaces it by the winding 18 of the 105 said polarized relay. If the subscriber should now decide to discontinue the call he 110 will release whatever switches have been operated when the receiver is placed upon the hook and will close the circuit of the meter magnet 9 at the back contact of the switch 115 hook. The magnet 9 will therefore energize at this time to restore its armature to normal position, thereby again bringing the springs 14, 15, etc., to normal position but without operating the counting wheels to 120 register the call. This non-operation of the register is due to the fact that the tooth 43 on the end of the arm 34 does not fall into the next succeeding tooth on the wheel 44 until the armature of the meter magnet 9 has 125 taken its second step or until the battery has been reversed through the talking circuit by the response of the called subscriber.

The same results above pointed out will take place in every instance where a call is initiated and then discontinued before the response of the called subscriber.

5 It is very often the case where a subscriber's substation meter is installed that certain subscribers will endeavor to make calls for which they should be charged and if possible prevent the operation of the meter to register this call. For instance, in the 10 circuits shown a calling subscriber might initiate a call and as soon as he hears the ringing current which is applied to the called subscriber's line for signaling he may by 15 quickly lowering and raising his receiver attempt to energize the meter magnet 9 to withdraw the arm 34 and open the circuits of the polarized relay 10 so that when the called subscriber does answer the arm 33 20 and its associated arm 34 will not be operated the second step to bring the tooth 43 behind the next tooth on the wheel 44, in which case when the call was completed and the receiver replaced upon the hook the call 25 would not be registered. In order to overcome this difficulty the spring 17 which controls the line circuit is put under the control of a slow acting element or weighted balance wheel 45. Now when the arm 34 moves to 30 the left upon the operation of the meter magnet 9, the upper end of the spring 17 attempts to follow the spring 16 but is retarded by the slow movement of the element 45 so that even though the subscriber does 35 not open the line circuit at the point 3 and 13 of the switch hook long enough to cause the connection to be released, the springs 16 and 17 will be held open upon the operation 40 of the meter magnet for a sufficient length of time to cause the release of the switches at the exchange.

It will be seen therefore that the meter control relay cannot be removed from the line circuit before the meter is operated 45 without releasing the connection and forcing the subscriber to call again.

It will be seen therefore that I have provided a very efficient type of substation meter which meets all the requirements of 50 party line or signal station line systems and also one which is absolutely certain in its operation and renders it impossible for any subscriber to call without being properly charged for said call.

55 Also it will be seen that I have provided means whereby the different windings of the meter magnet and its controlling relays are only included in the talking circuit for a short period of time during the establishment of a connection and that while listening in before a call or while conversing after the call is established the calling circuit is clear of any such windings or resistance.

Having described my invention I will

point out in the appended claims what I 65 consider to be new by Letters Patent.

What I claim as my invention is:

1. In a substation, the combination of a line circuit for said station, talking instrumentalities included in said line circuit, a 70 meter for said station, a controlling relay for said meter, means for completing a connection to a called line, said controlling relay normally excluded from the line circuit, means for including said relay in the 75 line circuit during the establishment of a connection, and means for again excluding said relay from the line circuit after the connection is completed and while the subscribers are talking.

2. In a substation, the combination of a line circuit for said station, talking instrumentalities included in said line circuit, a 80 meter for said station, a controlling relay for said meter, means for completing a connection to a called line, said controlling relay normally excluded from the line circuit, means for including said relay in the line circuit during the establishment of a connection, whereby said meter may be 85 operated, and means for again excluding said relay from the line circuit after the connection is completed and while the subscribers are talking.

3. In a telephone substation, a line circuit 95 therefor, talking instrumentalities associated with said circuit, a measured service device, a controlling relay for said device, normally inoperative, means whereby when a call is initiated said magnet is automatically placed in operative condition, and mechanism for preventing the subscriber from restoring said magnet to inoperative condition after the connection is established and before the called subscriber has 100 answered.

4. In a telephone system, talking instrumentalities and suitable circuits therefor, a calling device, a measured service device, a controlling relay for said device normally 110 inoperative, means controlled by the operation of said calling device for rendering said relay operative, and mechanism for preventing the calling subscriber from restoring said magnet to inoperative condition after the connection has been established and before the called subscriber has 115 answered.

5. In a telephone substation, a line circuit therefor, a calling device, a measured service device, a controlling relay for said device normally excluded from said line circuit, means controlled by said calling device for including said relay in the line circuit, means controlled by said calling device for 120 extending a connection from said line to a called subscriber, and means controlled by 125 the response of the called subscriber to op-

- erate said relay to in turn operate said measured service device over said first line.
6. In a telephone substation, the combination of talking instrumentalities and suitable circuits therefor, of a call register, a controlling relay for said register normally inoperative, a calling device also normally inoperative, means controlled by the operation of said device to extend a call, for rendering said relay operative, means for then controlling said relay to operate said meter, and means controlled by the operation of said meter for again rendering said relay inoperative.
- 15 7. In a telephone substation, the combination of talking instrumentalities and suitable circuits therefor, of a call register, a controlling relay for said register normally inoperative, a calling device also normally inoperative, means controlled by the operation of said device to extend a call, for rendering said relay operative, means controlled by the called subscriber for then controlling said relay to operate said meter, and means controlled by the operation of said meter for again rendering said relay inoperative.
- 20 8. In a telephone substation, the combination of talking instrumentalities and suitable circuits therefor, of a call register, a controlling relay for said register normally inoperative, a calling device also normally inoperative, means controlled by the operation of said device to extend a call, for rendering said relay operative, means controlled by the called subscriber for then controlling said relay to operate said meter, means controlled by the operation of said meter for again rendering said relay inoperative, and
- 25 40 a mechanism for preventing the calling subscriber from restoring said relay to inoperative condition after a connection has been established and before the called subscriber answers.
- 45 9. In a telephone substation, a line circuit therefor, talking equipment associated with said line circuit, a measured service device, a controlling relay for said device having a pair of windings normally excluded from the line circuit, a calling device, means controlled by the initial operation of said calling device for including one of said windings in said line circuit, the inclusion of said winding adapted to control said relay
- 50 55 to partially operate said measured service device and to again exclude said winding from the line circuit, means controlled by the partial operation of said measured service device for including the other of said windings in the line circuit, means for then controlling said relay through the medium of said last winding to again partially operate said measured service device and to again exclude said last winding from the
- line circuit, and means for then completing the operation of said measured service device to register the call.
10. In a telephone substation, a line circuit therefor, talking equipment in said line circuit, a measured service device, a magnet for controlling said device to register a call, a normally open circuit for said magnet, an armature for said magnet normally held in attracted position, means for allowing said armature to fall back part way to close the circuit of the magnet at one point, and for then allowing said armature to fall back all the way, means for then closing the circuit of said magnet at another point whereby said magnet is energized to restore its armature to attracted position to again open the circuit of said magnet and register the call.
- 15 11. In a telephone substation, a line circuit, talking equipment associated with said line circuit, a meter, a magnet having an armature for operating said meter, said armature normally inoperative to operate said meter, a circuit for said magnet normally open, means for extending a connection from said substation to a called substation, means controlled by the initiation of a call for closing the circuit for said magnet at one point, means controlled by the response of the called subscriber for rendering said armature operative to operate said meter, and means controlled by the hanging up of the receiver at the calling substation for operating said magnet to in turn operate said meter.
- 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945

14. In a telephone system, a line circuit therefor, suitable talking equipment included in said line circuit, a normally inoperative meter, a calling device, means for operating said meter, means controlled by the operation of said calling device for rendering said meter partially operative, means for extending a connection from said substation to a called station, means controlled by the response of the called subscriber for

rendering said meter fully operative, means for then operating said meter, and means for preventing a calling subscriber from holding said meter inoperative after the connection has been established and before the 15 called subscriber has answered without releasing the connection.

Signed by me at Chicago, Cook county, Illinois, this 6th day of December, 1917.

JOHN ERICKSON.
